JOHN H. WEIDMAN, OF MARCELLUS, NEW YORK

MECHANICAL DISHWASHER

Original application filed March 29, 1927, Serial No. 179,249. Divided and this application filed April 21, 1930. Serial No. 446,011.

This invention relates to a mechanical dishwasher of the class set forth in my Patent No. 1,757,258, May, 6, 1930, of which this application is a division.

5 The main object is to obtain a more uniform distribution of the washing fluid throughout the interior area of the vat from top to bottom with greater force and with less water and power than has heretofore been practiced.

Another object is to arrange the open work dish-supporting trays at different levels above and below the revolving head so that the dishes therein may receive the direct impact of the jets of water issuing from the orifices of said head as the latter is rotated and to cause the jets of water to traverse the entire areas of both trays and interior of the vat.

15 A further object is to provide means whereby the food particles displaced from the dishes in the lower tray are separated from the cleaner water and the latter recirculated from the bottom of the vat through the distributing head and thereby to reduce to a minimum the amount of water required for dish-washing purposes.

Another object is to provide means whereby fresh water may be introduced through 20 the distributing head independently of the recirculating means for rinsing or washing purposes as may be desired.

A further object is to provide means whereby the washing fluid may be drained off from 25 the vat and from the recirculating means while the distributing head is at rest or even when fresh water is being supplied thereto, thus permitting the interior of the vat to be thoroughly cleansed by the distribution of 40 the fresh water therein while drawing off the foul water from the bottom.

Other objects and uses relating to specific parts of the machine will be brought out in the following description.

45 In the drawings:

Figure 1 is a top plan of a mechanical dishwasher embodying the various features of my invention, a portion of the cover being broken away to show the interior mechanism.

Figure 2 is an enlarged vertical sectional view taken in the plane of line 2—2, Figure 1.

Figure 3 is an enlarged detail vertical sectional view taken in the plane of line 3—3, 55 Figure 2, showing a portion of the pump case broken away.

Figure 4 is an enlarged top plan of the central portion of the revoluble distributing head.

60 Figure 5 is an enlarged vertical sectional view through the center of the distributing head taken in the plane of line 5—5, Figure 4.

Figure 6 is an enlarged detail sectional view taken on line 6—6, Figure 2.

Figure 7 is an enlarged transverse sectional view of a portion of the distributing head showing the angular disposition of the discharge orifices in opposite sides thereof. 70

As illustrated, this machine comprises a vat —1— which is substantially square or rectangular in top plan and is provided with a frusto-conical bottom —2— and a substantially flat top lid or cover —3—, the latter 75 movable or removable as desired.

The upper end of the vat is provided with an outwardly, upwardly and downwardly turned flange —4— forming a substantially horizontal ledge —5— and a slightly raised 80 bead —6— surrounding the ledge —5—, the rear side of the top portion of the vat being extending above the remaining portions to form a back flange —7—.

The area of the cover —3— is slightly 85 greater than the interior area of the vat so that its marginal edges may rest upon the ledge —5— where it is held against lateral movement by the adjacent walls of the bead —6— but may be removed and replaced at 90 will.

Suitable dish-supporting trays or open-work baskets —8— and —9— are removably supported at different levels within the vat, the lower tray —8— being supported upon 95 the marginal edges of the bottom —2— while the upper tray —9— is supported at its upper end upon the marginal ledge —5— thus leaving an intervening space between the two trays for the reception of a rotary distribut- 100

ing head and its supporting means presently described.

The vat —1— is provided in one side with a water-tight gland —10— registering with 5 the space between the lower and upper trays —8— and —9— but somewhat nearer the upper tray for receiving and supporting a water intake or inlet pipe —11— which extends horizontally through said gland from 10 the exterior of the vat to approximately the center or axis thereof.

The inner end of the inlet pipe —11— is provided with an up-turned elbow —12— upon which is journaled the central portion 15 of a distributing head —13— adapted to rotate about the axis of the vat and provided with oppositely extending arms of equal length and weight for counter-balancing purposes.

20 This distributing head —13— is hollow or tubular and is provided with a central opening communicating with the interior of the water inlet pipe —11—, Figure 5, the opposite ends of said head being preferably closed 25 while the remaining portions are provided with lower and upper sets of discharge nozzles —14— having relatively narrow fan-shaped orifices —14'—, those of one set being arranged in staggered relation to those of 30 the other set as shown more clearly in Figure 2 so as to distribute the jets of water issuing therefrom over practically the entire area of the interior of the vat from top to bottom thereof.

35 The distributing head —13— is rotatable in a horizontal plane within the space between the lower and upper trays —8— and —9— but somewhat nearer and directly below the upper tray which is adapted to carry 40 the less soiled dishes such as glassware and the like while the lower tray is preferably used to support the plates, platters and analogous articles to which the food products are more liable to adhere.

45 The orifices —14'— are relatively narrow transversely of the tubular head —13— but are elongated lengthwise of said head and diagonally thereto to cause the water to issue therefrom with considerable force in the 50 form of fan-shaped spray jets in overlapping relation without interfering with each other.

The orifices of the upper set are preferably vertical to discharge their jets vertically against the dishes in the upper tray while 55 the orifices in the nozzles of the lower set at opposite sides of the axis of rotation of the head are deflected laterally and downwardly in reverse directions at relatively slight angles to said axis to cause the jets issuing 60 therefrom to rotate the head.

65 Under these conditions foreign matter which may adhere to the dishes in the lower tray —8— will be displaced and caused to lodge on the conical bottom —2— away from the dishes while the foreign matter which is

displaced from the dishes in the upper tray will be comparatively slight and precipitated into the lower tray to be again displaced by the downwardly spreading jets 70 from the distributing head.

The outer end of the inlet pipe —11— is connected to an upright pipe T —15— having its upper end connected to another pipe T —16—, one branch of which is connected to a cold water supply pipe —17— and the 75 other end to a hot water supply pipe —17'—.

These supply pipes —17— and —17'— are provided with separate valves —18— and —18'— operable at will to control the fresh 80 water supply to the distributing head —13— through the inlet pipe —11—.

The lower end of the pipe T —15— is connected by a pipe —19— to the pressure side of a centrifugal pump —20— having its suction side connected to a discharge pipe 85 in the apex of the conical bottom —2— of the vat —1—.

This outlet pipe —21— is extended through a water-tight gland —22— in the apex of said bottom and is provided with 90 a screen or filter cap —23— within the vat and just below the lower tray —8— to prevent the entrance of solids into the pump.

The pump —20— and motor —24— are located directly beneath the bottom —2— 95 of the vat —1— and are supported by a bracket —25— which in turn is secured by any suitable fastening means to the bottom —2—.

The lower side of the pump case —20— 100 is provided with a drainage —26— leading therefrom and including therein a valve —27— and a trap —28—.

The valve —27— may be opened and closed by means of an operating rod —29— 105 which extends upwardly along the rear side of the vat through an opening in the marginal bead —6— and is provided with a member —30— by which it may be operated.

The pipe —19— is provided with a check 110 valve —31— between the inlet pipe —11— and pressure side of the pump —20— to allow the filtered water entering the discharge pipe —21— to be recirculated by the pump —20— 115 through the pipe —19— and inlet pipe —11— and thence through the distributing head —13— and into the interior of the vat, thus permitting the use of the same water for recirculation, if desired, the check valve —31— 120 serving to prevent the down-flow of fresh water from either of the supply pipes —17— and —18— into the pump through the pipe —19— and also to prevent return flow of the water from the inlet —11— through the pipe —19— to the pump.

125 Current may be supplied to the motor from any available source of power through cables —32— to which is connected an electric switch —33— located directly under the flange —4— at the front of the machine and 130

operable at will through the medium of a suitable handle —34—, Figure 2.

The lower tray —8— is provided with a central relatively smaller supplemental tray 5 —8'— for receiving knives, forks, spoons and analogous articles, said supplemental tray being provided with a perforated bottom to allow the washing fluid to drain therefrom and is held against lateral displacement by a ring —8''— on the tray —8—.

Operation

Assuming that the trays —8— and —9— with the dishes to be washed therein are placed in operative position within the vat and that the lid or cover —3— is closed, then, one or the other or both of the valves —18— and —18'— may be opened to allow fresh water to pass through the inlet pipe —11— and thence through the distributing head —13— into the interior of the vat so that the exit of the water through the lower nozzles will cause the rotation of the head by reason of the angular disposition of the nozzles relatively to the axis of rotation.

The water issuing from the several nozzles of the distributing head in the form of fan-shaped sprays or jets will be forced under considerable pressure through the open work trays —8— and —9— and against the dishes therein with more or less glancing impact due to the spread of the jets and to the rotation of the head, this operation being continued as long as may be desirable to use 35 fresh water.

Under these conditions if the drainage valve —27— is opened the filtered water resulting from the washing of the dishes will escape through the drainage outlet —28— through any suitable waste pipe, not shown.

On the other hand, if the drainage valve —27— is closed a limited quantity of fresh water may be allowed to collect in the vat sufficient to cover the screen —23— whereupon the valves —18— and —18'— in the 45 fresh water supply pipes may be closed and the electric motor started by the proper operation of the switch member —34—.

The operation of the motor —24— will cause a corresponding operation of the pump —20— to draw the filtered washing fluid through the discharge pipe —21— and force it upwardly through the pipe —19—, through the check valve —31— and thence 55 through the inlet pipe —11— and distributing head —13— to the interior of the vat which causes the rotation of the distributing head to effect a thorough cleansing of the dishes in both trays —8— and —9—.

The washing fluid precipitated to the bottom of the tank is again recirculated by the pump —20— through the pipes —19—, —11—, and distributing head —13—, this 65 recirculating operation being continued as long as desired or until the dishes are thor-

oughly cleansed at which time the drainage valve —27— and one or both of the fresh water supply valves —18— and —18'— again open to allow the introduction of fresh water into the interior of the vat 70 through the distributing head —13— for rinsing purposes.

After the dishes have been properly rinsed the fresh water supply valves —18— and —18'— may be closed and the trays —8— 75 and —9— with the dishes therein allowed to remain in the vat until thoroughly dried.

The upper tray —9— with the dishes therein may then be removed to permit the removal of the supplemental tray —8'— 80 and dishes from the lower tray, whereupon the cleansed and dried dishes from all of the trays may be stored away for future use, the trays being then free for re-use when desired.

It will be noted on reference to Figure 2 that the supplemental tray —8'— is removably supported in the lower tray —8— and when removed the screen —23— may also be removed to permit cleansing thereof and 85 also to permit drainage of any refuse which may lodge on the bottom of the vat through the outlet pipes —21— and —28— when the valve —27— is opened.

The tray —8— is also removable through 90 the open upper end of the vat when desired but is preferably left in place.

It will also be noted that when the upper tray —9—, supplemental tray —8'— and screen —23— are removed and the valve 95 —27— opened fresh water, either hot or cold, may be projected into the interior of the vat through the nozzles in the head —13— causing the rotation of the latter and a thorough cleansing of the interior of the 100 vat and lower tray —8— when in place, the fresh water being allowed to flow out through the drainage pipe —21—, pump —20— and waste pipe —23— to thoroughly cleanse those parts, all of which affords a 105 convenient means for maintaining the interior of the vat and water passages in a thoroughly sanitary condition.

It will be further noted that under all 110 washing conditions any grease or refuse which may be liberated from the dishes is precipitated to the bottom of the vat below the level of the lower tray where it remains in a more or less quiet state without liability 115 of being recirculated through the vat and on to the dishes, but may be withdrawn at the end of the washing operation by simply removing the screen —23— and introducing fresh water into the vat through the head —13— as previously explained whereby the 120 fresh water will carry off the refuse through the pipe —21—.

In other words, during the recirculation 125 of the washing fluid by the operation of the pump —20— the filtered water passing 130

through the screen —23— is by-passed around the outside of the vat through the pipes —19— and —11— rather than from the bottom upwardly through the vat there-
5 by avoiding the agitation and projection of the fouled water against the dishes.

On the other hand, where the water pressure is sufficient the entire washing and rinsing operations may be performed with
10 pure fresh water to the exclusion of the re-circulating means in which case the screen —23— might be removed and the valve —27— opened to allow the foul matter to be carried off from the vat as fast as it is
15 displaced from the dishes.

What I claim is:

In a mechanical dishwasher, a rotatable water-receiving and distributing head provided with a series of spaced discharge
20 nozzles in opposite sides thereof, the nozzles in one side being inclined to the plane of rotation and those in the other side being perpendicular to said plane, the nozzles of each series having their mouths elongated in
25 parallel planes diagonal to the direction of movement of the head to produce parallel spaced fan-shaped jets, and means for introducing water in said head under pressure.

In witness whereof I have hereunto set
30 my hand this 15th day of April, 1930.

JOHN H. WEIDMAN.
